UNITED STATES PATENT OFFICE.

JOSEPH J. PARMENTER, OF CHICAGO, ILLINOIS.

SHOE-PROTECTOR.

1,304,593.

Specification of Letters Patent. Patented May 27, 1919.

Application filed March 12, 1917. Serial No. 154,153.

To all whom it may concern:

Be it known that I, JOSEPH J. PARMENTER, a citizen of the United States, residing in Chicago, in the county of Cook and State of Illinois, have invented certain new and useful Improvements in Shoe-Protectors, of which the following is a specification.

My invention relates in general to automobile accessories and more particularly to a protector for the shoes of lady drivers. In driving automobiles it is necessary to frequently actuate the controlling pedals which subjects the toes, soles and counters of the shoes of the operator to constant rubbing and wear. Ladies' shoes are of such fine texture that they soon become abraded and unsightly. This objection has led to the placing of pads on the pedals made of materials which will be less injurious to ladies' shoes than the metal of which the pedals are made. This expedient has proved only partly successful as the shoes are still subjected to unusual wear through contact with the various operating mechanisms of the modern automobile.

The object of my invention is to provide a protector for the portions of ladies' shoes which are exposed to injury and wear in driving automobiles. A further object of my invention is to provide a protector for the shoes of lady automobile drivers which may be readily placed in position on the shoes and while made of materials capable of withstanding the necessary wear and rubbing will be attractive in appearance.

A still further object of my invention is to provide a shoe protector of the class described which will be simple in construction, durable in use and readily placed upon and removed from the shoe.

My invention will be more fully disclosed with reference to the accompanying drawing in which the same is illustrated in a convenient and practical form and in which—

Figure 1 is a side elevational view showing the protector in position upon a lady's shoe; and

Fig. 2 is a view of the protector removed from the shoe and folded into compact form.

Similar reference characters are used to designate similar parts in the two figures of the drawing.

Reference letter A indicates the portion of the protector which underlies the sole of the shoe, and is preferably made of some durable and relatively stiff material such as

leather. The under surface of the portion A is preferably covered with a layer of sheet rubber *a* in order to afford a greater frictional contact with the parts engaged which are to be actuated by the sole of the foot in operating an automobile.

B designates the portion of the protector which overlies the toe of the shoe and extends around the same to the outer edge of the sole portion A to which it is secured in any suitable manner.

In order to protect the counter of the shoe the portion C is provided which is of, a shape and size to closely fit around the counter of the shoe. The portion C is made of any suitable material which will withstand the wear and rubbing due to contact with the mechanism on the floor of the automobile. D designates straps which extend from the opposite sides of the counter portion C to the corresponding sides of the toe portion B, such straps being preferably elastic so that they will serve to retain both the toe and counter portions in secure engagement with the shoe. E designates a transverse strap connected at its ends to the opposite elastic straps D and adapted to extend under the instep so as to prevent the counter portion C of the protector from slipping upwardly out of proper position upon the shoe.

It will be observed that my improved protector may be readily placed upon the shoe and when in such position will afford protection to the sole, the toe and the counter of the shoe so that such portions of the shoe which are most exposed to wear are prevented from being injured through contact with the operating mechanism of an automobile. The counter and toe portions serve to mutually retain each other in protecting positions upon the shoe through the medium of the straps D.

When the protector is not in use it may be folded into compact form as shown in Fig. 2, by reason of the flexible straps D permitting the counter portion C to be inserted in the space between the sole and toe portions.

From the foregoing description it will be observed that I have invented an improved protector for the shoes of lady automobile drivers which may be readily placed upon and removed from the shoe and when in position will be securely retained there so as to overlie and assume the wear which would otherwise be imposed upon the shoe.

What I claim as my invention is—

A protector having a toe portion and a heelless counter, the toe portion comprising a sole of relatively stiff material, a member secured to the upper portion of the sole for overlying the edges of the shoe, and elastic connections between the counter and toe portion, the counter adapted to surround the

rear portion of the shoe above the heel and arranged when not in use to be placed within the toe portion. 10

JOSEPH J. PARMENTER.
